US0D1106065S

(12) **United States Design Patent** (10) **Patent No.:** **US D1,106,065 S**
(45) **Date of Patent:** **** Dec. 16, 2025**

(54) **CONTROLLER**

(71) Applicant: **Denali Electronics LLC**, East Greenwich, RI (US)

(72) Inventor: **Nathan Bastien**, Exeter, RI (US)

(73) Assignee: **Vision X Offroad, LLC**, Auburn, WA (US)

(**) Term: **15 Years**

(21) Appl. No.: **29/823,817**

(22) Filed: **Jan. 20, 2022**

(51) **LOC (15) Cl.** **13-02**

(52) **U.S. Cl.**

USPC **D13/110**

(58) **Field of Classification Search**

USPC D13/101, 103, 107, 108, 110, 118, 133, D13/137.1, 162, 162.1, 199
CPC . H01H 1/16; H01H 1/18; H01M 10/46; H02J 7/0042; H02J 7/0047; H02M 1/10

See application file for complete search history.

(57) **CLAIM**

The ornamental design for a controller, as shown and described.

DESCRIPTION

FIG. 1 is a front view of a controller showing the claimed design;

FIG. 2 is a rear view of the controller of FIG. 1;

FIG. 3 is a top view of the controller of FIG. 1;

FIG. 4 is a bottom view of the controller of FIG. 1;

FIG. 5 is a left view of the controller of FIG. 1;

FIG. 6 is a right view of the controller of FIG. 1;

FIG. 7 is a perspective front, top, right of the controller of FIG. 1;

FIG. 8 is a perspective front, top, left of the controller of FIG. 1;

FIG. 9 is a perspective rear, top, right of the controller of FIG. 1;

FIG. 10 is a perspective rear, top, left of the controller of FIG. 1;

FIG. 11 is a perspective front, bottom, right of the controller of FIG. 1;

FIG. 12 is a perspective front, bottom, left of the controller of FIG. 1;

FIG. 13 is a perspective rear, bottom, right of the controller of FIG. 1; and,

FIG. 14 is a perspective rear, bottom, left of the controller of FIG. 1.

The broken lines shown represents environmental subject matter and form no part of the claimed design.
